[57] **CLAIM**

The ornamental design for a combined compressed gas inhaler facepiece and base, as shown and described.

DESCRIPTION

FIG. 1 is a perspective view of a combined compressed gas inhaler facepiece and base showing our new design, shown in storage position;

FIG. 2 is a perspective view of the facepiece, shown in inverted position for use;

FIG. 3 is a top view of the facepiece shown in FIG. 1;

FIG. 4 is a front view of the facepiece;

FIG. 5 is left side view of the facepiece;

FIG. 6 is a rear view of the facepiece;

FIG. 7 is a bottom plan view of the facepiece as shown in FIG. 1;

FIG. 8 is a top view of the base;

FIG. 9 is a side view of the base; and,

FIG. 10 is a bottom view of the base.

The broken line showing the container in FIGS. 1 and 2 is for illustrative purposes only and forms no part of the claimed design.
